UNITED STATES PATENT OFFICE.

FREDERICK W. GOUDY, OF CHICAGO, ILLINOIS, AND JOSEPH W. PHINNEY,
OF MEDFORD, MASSACHUSETTS.

DESIGN FOR A FONT OF TYPE.

SPECIFICATION forming part of Design No. 32,298, dated February 27, 1900.

Application filed February 1, 1900. Serial No. 3,650. Term of patent 14 years.

To all whom it may concern:

Be it known that we, FREDERICK W. GOUDY, of Chicago, in the county of Cook and State of Illinois, and JOSEPH W. PHINNEY, of Medford, in the county of Middlesex and State of Massachusetts, have invented and produced a new and original Design for a Font of Type, of which the following is a specification.

This design comprises capital letters, small letters, and Arabic numerals.

The general characteristic of the font is an unshaded medium-faced letter having small serifs, the angular letters being quite narrow or thin in proportion to the round letters. This is especially noticeable in comparing, for example, the capital letters B, E, F, J, L, P, and R with the capital letters C, G, O, Q, and U. The serifs of the capital letters C, F, G, S, and T and the upper serifs of the capital letters E and Z run into a point slightly above the upper line of the letter and down diagonally somewhat more below the upper line of the letter, the portion below the line being somewhat longer than the portion above, the termination of the letter being at an angle of about forty-five degrees with the vertical, thus resembling somewhat the point and one spur of a fish-hook. In the lower serifs of the capital letters E and Z the design is reversed, so that the serifs of capital E approach each other. The serifs of capital T point outwardly from each other.

The lower portion of the capital letter C ends abruptly with but scarcely any upturned portion, and the capital letter G resembles the capital letter C, except that its characteristic is a vertical portion standing, as it were, upon the toe of the letter C. The capital letter Q is like the capital letter O with a short cross-mark resting on the line. The capital letter W is made of two capital V's crossed, and the lower portion of the capital

letter Z is slightly longer than the upper portion. The serifs of the other letters having serifs are horizontal.

45

The small letters do not have the narrow characteristic of the capitals, though their serifs terminate in a point, and the small letter e resembles the capital letter C. The bow-shaped portion of the small letters b, d, p, and q is not a regular curve, the lower portion of the curves being drawn on a longer radius than the upper portion. The characteristic horizontal mark of the small letter e is not, in fact, quite horizontal, running from the middle of the circular portion of the letter upward to meet the upper portion. The small w, like the capital W, is made of two v's crossed.

50

The loop portion of the numerals 3 and 5 is quite large in comparison with the rest of the numeral and extends below the line, while the loop portion of the figures 6 and 9 is quite large in comparison with the rest of the numeral, the upper portion of the numeral 6 and the lower portion of the numeral 9 being curved considerably and extending but a short distance vertically above and below the loop, respectively.

60

What we claim as our invention is—
The design for a font of type as herein shown and described.

70

In testimony whereof we have hereunto set our names, the said GOUDY this 23d day of January, 1900, and the said PHINNEY this 26th day of January, 1900.

WALTER S. MARDER,

FRANK B. SNELL.

Witnesses to J. W. P.:

GEORGE O. G. COALE,

E. A. GUILD.

It is hereby certified that Letters Patent No. 32,298, granted February 27, 1900, upon the application of Frederick W. Goudy, of Chicago, Illinois, and Joseph W. Phinney, of Medford, Massachusetts, for a "Design for a Font of Type," was erroneously issued to said Goudy and Phinney as owners of the entire interest in said invention; that the said Letters Patent should have been issued to the *American Type Founders' Company, of New York, N. Y.*; said American Type Founders' Company being assignee of the entire interest therein; and that the said Letters Patent should be read with this correction therein that the same may conform to the record of the case in the Patent Office.

Signed, countersigned, and sealed this 20th day of March, A. D., 1900.

[SEAL.]

THOS. RYAN,

First Assistant Secretary of the Interior.

Countersigned:

C. H. DUELL,

Commissioner of Patents.
